[57] CLAIM

The ornamental design for a fetal communication device, as shown and described.

DESCRIPTION

FIG. 1 is a front elevational view of a fetal communication device showing our new design;

FIG. 2 is a left side elevational view thereof, the right side elevational view being a mirror image;

FIG. 3 is a rear elevational view thereof; and

FIGS. 4 and 5 are respectively top and bottom plan views thereof.

Fig. 1.

Fig. 2.

Fig. 3.

Fig. 4.
